UNITED STATES PATENT OFFICE.

ERNEST CANTELO WHITE, OF NEW YORK, N. Y., ASSIGNOR OF ONE-HALF TO R. FENTON FISHER, OF PHILADELPHIA, PENNSYLVANIA.

ELECTRIC-LIGHTING FIXTURE.

Application filed May 5, 1925. Serial No. 28,060.

My invention relates to the construction of all types of electric light fixtures including wall brackets, ceiling fixtures, chandeliers, table lamps, floor lamps, adjustable fixtures 5 and all appliances or parts thereof which contain or include a lamp socket.

In my copending application, Ser. No. 10,182 filed February 19, 1925, I described one method of producing a lighting fixture 10 from moulded material in order to facilitate the assembly of a fixture with the necessary wires and wiring devices. The objects of my present invention are to furnish an improved construction for similar purposes and for 15 the support of globes or shades.

In the accompanying drawings, Fig. 1 is the side view of an electric wall bracket which is moulded in two halves, joined on the line A—A, the upper portion of the 20 wall plate being shown in vertical section; Fig. 2 is a horizontal view of the bracket as attached to a wall with the upper half of the bracket removed and the supporting centre knob shown in section; Fig. 3 is a 25 cross-sectional view on the line B—B of Fig. 2; Fig. 4 is a cross-section of one of the arms on the line C—C of Fig. 2; Fig. 5 is a back view of the wall bracket; Fig. 6 is a front view of the centre knob used to support the 30 bracket; Fig. 7 is a cross-sectional view similar to Fig. 3 showing the position of an electric lamp and a shade when used, and also showing the position of an attachment 35 plug when connected to the socket; Fig. 8 is a front view of the bracket; Fig. 9 is a a plan view of one of the threaded socket covers; Fig. 10 is a cross-section thereof; Fig. 11 is a cross-section of another form of threaded 40 socket cover; Fig. 12 is a cross-section of a shade supporting ring; Fig. 13 is a view of the twin lamp socket used in the fixture.

In carrying out my invention according to the illustrated embodiment thereof, I provide parts moulded in insulating material 45 including half bodies 1 and 2 which are exactly alike so that two parts from the same mould may be assembled as shown.

A twin socket 3, having a push button 4 and wires 5, 5 connected to its binding screws 50 6, 6 is inserted endwise into the lower half-body 1, the wires being laid into the grooves 16 and the two ends of the push button 4 fitting into grooves 7, 7. The upper half-body 2 is then slipped over the upper end of 55 the socket and into an assembled position.

Two threaded socket covers of moulded insulating material, 8 and 9, having internal threads 10 which fit the outside of the threaded screw-shells of the twin lamp socket, are then screwed onto the said lamp socket until 60 the ends of the said socket covers seat respectively into the rabbets 11 and 12 of the half-bodies 1 and 2.

Inasmuch as the twin socket 3 is composed of parts firmly riveted together, the socket 65 is thus partially utilized as a bolt and the two threaded socket covers as nuts to lock the two half-bodies together so as to form, in combination with the socket covers, a complete bracket which may then be supported 70 on an outlet by means of a knob 13 and a threaded stud 14.

The knob 13 has an internal taper 15 which fits over a corresponding conical surface of the two half-bodies so that when the bracket 75 is drawn back against the wall by the knob 13, the conical surfaces of the two half-bodies are drawn tightly together by the internal taper of the knob.

It will be observed from the above description that the socket 3 is held rigidly in position by the counteracting pull of the two socket covers so that it is not necessary to utilize the push-button 4 in the groove 7 to 80 position the socket in the fixture. This prevents binding of the push-button which permits a more satisfactory use of the switch 85 operated thereby.

Figs. 7 and 8 show the bracket assembled with a threaded socket cover 8', which is 90 similar to socket cover 8, substituted for the socket cover 9 shown in Figs. 1 and 3 and with an additional moulded ring 17 in position outside of the upper threaded socket cover. This ring 17 is made to slip 95 over the threaded socket cover and has a flange 18 of approximately the same diameter of the flange 19. When assembled, the general position is that shown in Fig. 8 when no shade is used.

If it is desired to utilize a glass shade, it is better to use one having a plain hole without the usual lip. The socket cover 8' and the ring 17 are then removed from the socket, the member 8' is inserted through the 100 opening in the shade from the inside, the ring 17 is slipped over the member 8', which is then screwed back onto the socket shell, giving a complete assembly as illustrated in Fig. 7 after the lamp is inserted. The rab- 110

bet 12 is made deep enough so that when the flanges 19 and 18 are gripping the glass shade and therefore separated by the thickness of the shade, the inside end of the 5 threaded socket cover will still be entered partly into the said rabbet in order to centre the various parts with the axis of the main body of the bracket. When screwed up tightly, the actual bearing will be between the 10 ring 17 and the half-body 2. The members 8 and 8' are moulded with a number of small projections 20 which may be conveniently engaged by the operator's fingers inside of a shade in order to screw the parts together 15 until some friction is established between the lower side of the flange 19 and the shade, after which they may be further tightened by turning the shade itself at the same time.

The inside dimensions of the flange 19 20 permit the use of a standard two-piece attachment plug as shown in dotted lines in Fig. 7. The total length of the part 8 is such that when the cap is removed from the attachment plug the screw portion of the 25 plug which remains in the socket will be practically concealed from all angles of view above the horizontal.

The wall plate portion of the half-bodies 1 and 2 may be moulded with bridges 21 30 and 22 spaced from the back edge of the bracket as illustrated in Figs. 1 and 2 and provided with notches 23 and 24, as shown in Fig. 5, in order to provide for supporting the bracket on a hook attached to an outlet 35 box. For example, when the bridge 22 is utilized for this purpose, the notch 24 prevents the bracket from slipping sideways on the hook and the space between the bridge 22 and the wall, provides room for 40 the projecting edges of an outlet box. The hooks commonly used for this purpose are attached to the electric outlet by means of a threaded stud so that the distance of the hook from the wall surface may be adjusted 45 to fit the position of the bridge of a bracket as will be understood by anyone versed in the art of installing electric lighting fixtures.

An important feature of my improved 50 bracket is the provision of two arms instead of one to support the socket housing. This not only enables the provision of more ample space 16 for a conductor in each arm, but also provides a more rigid construction 55 and particularly facilitates the use of the push-button switch in the position shown, so that the front button may be pushed to turn on the light and the rear button operated from the open space between the arms 60 to turn it off.

The new methods of construction herein described are applicable to all other forms of lighting fixtures as well as to wall brackets and my invention, therefore, includes all 65 devices in which the construction and assem-

bly of parts include what I claim as new, which is:

1. An electrical lighting fixture comprising a lamp socket, electrical conductors leading thereto, a housing for said socket and conductors formed of moulded insulating material in a plurality of parts, and threaded means adapted to screw onto the outside of the screw-shell of the lamp socket for holding the said housing together in assembled relation. 70 75

2. An electric lighting fixture comprising a lamp socket, conductors leading thereto, a housing for said socket and conductors formed of moulded insulating material in a plurality of parts and means integrally moulded with one portion of the said housing for sliding engagement with a fixture hook on an electric outlet. 80

3. An electric lighting fixture including a lamp socket having a metallic screw-shell, conductors leading to the said socket, a housing for said socket and conductors formed of moulded insulating material in a plurality of parts, and a shade retaining member formed of moulded insulating material and threaded internally to screw onto the outside of the said screw-shell. 85 90

4. An electric lighting fixture consisting of two lamp sockets arranged on the same axis and pointing in opposite directions, conductors leading thereto, a housing for the said sockets and conductors formed of moulded insulating material in a plurality of parts, two of the said parts being adapted to screw onto the outside of the said screw-shells and to hold the rest of the said housing together in an assembled relation. 95 100

5. An electric lighting fixture comprising a lamp socket, conductors leading thereto, a housing for the said socket formed of moulded insulating material, a plurality of arms spaced apart and supporting the said housing and moulded integrally therewith and a space in each of said arms adapted to accommodate one of the said conductors. 105 110

6. An electric wall bracket comprising a push-button socket, a socket-housing therefor, a wall plate, two arms spaced apart and supported by the wall plate and attached to the said socket-housing, one end of the push-button of said socket being disposed in the space between the said arms. 115

7. An electric lighting fixture formed of moulded insulating material, the portion of said fixture adapted to bear against the wall being made in two parts, means for attaching the said fixture to an electric outlet, the said attaching means being adapted to draw the said two parts together in assembled relation when tightened up so as to draw the said fixture against the wall. 120 125

8. An electric wall bracket comprising a push-button lamp socket having two screw-shell contacts arranged on the same axis and 130

- pointing in opposite directions, conductors leading thereto, a housing for said socket and conductors formed of moulded insulating material in a plurality of parts, two parts of said housing being adapted to screw onto the outside of said screw-shells so as to hold other parts of the housing together in assembled relation, the said housing including two arms horizontally disposed, one end of the push-button being disposed in the space between the two arms, a portion of the said housing being formed as a wall plate, and means for attaching the said wall plate to an electric outlet.
9. An electric lighting fixture including a lamp socket having a metallic screw-shell, an inner shade ring formed of insulating material and threaded internally to screw onto the outside of said screw-shell, the said inner shade ring being adapted to be inserted through the opening in a shade and having a flange adapted to bear against the inside surface of the said shade, an outer shade ring adapted to slip over the inner shade ring and bear against the outer surface of the said shade, and a bearing for the outer shade ring, said bearing being fixed in relation to the said screw-shell when the fixture is assembled.

Signed at New York, N. Y., on this 2nd day of May, 1925.

ERNEST CANTELO WHITE.
